(57) **CLAIM**

The ornamental design for a water fillable securing base with tethered tennis ball, as shown and described.

DESCRIPTION

FIG. 1 is a front perspective view of a water fillable securing base with tethered tennis ball showing my new design, and shown in a state wherein said tennis ball is partially deployed from said base;

FIG. 2 is a front view thereof, showing said ball secured by said base;

FIG. 3 is a view taken from the top of FIG. 2;

FIG. 4 is a rear view thereof showing said ball partially deployed from said base;

FIG. 5 is a side view thereof, taken from the right of FIG. 1;

FIG. 6 is a side view thereof, taken from the left of FIG. 2;

FIG. 7 is a view taken from the bottom of FIG. 2; and,

FIG. 8 is a sectional view taken in the direction of the arrows upon the line 8—8 of FIG. 2.
